(57) **CLAIM**

The ornamental design for a tub for bathing, as shown and described.

DESCRIPTION

In a preferred embodiment, the nature of this product is as a plumbing fixture in the form of a bathing tub primary useful for washing the human body.

FIG. 1 is a right, top, front perspective view of a tub for bathing embodying my new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof; and,

FIG. 7 is a bottom plan view thereof.

The broken line representations of a water jet structure in FIGS. 1-3 and 6-7, a drain in FIGS. 2-7, an overflow/control and recessed wall structure in FIGS. 1-3 and 7, and an opening in FIGS. 2, 4 and 6-7 are for the purpose of illustration only, and form no part of the claimed design.
